(57) **CLAIM**

The ornamental design for a grip for disposable menstrual cup, as shown and described.

DESCRIPTION

FIG. 1 is a perspective view of a grip for disposable menstrual cup in accordance with the new design;

FIG. 2 is a front plan view thereof;

FIG. 3 is a rear plan view thereof;

FIG. 4 is a right side view thereof;

FIG. 5 is a top plan view thereof;

FIG. 6 is a bottom plan view thereof; and,

FIG. 7 is another perspective view showing the grip for disposable menstrual cup after using by a user.

The broken lines shown in the figures are for the purpose of illustrating usage and environment, and form no part of the claimed design.
